INVENTOR
Daniel P. Mahoney,
By Robert Robert, his
Attorney.

UNITED STATES PATENT OFFICE.

DANIEL P. MAHONEY, OF CAMBRIDGE, MASSACHUSETTS.

COAL CHUTE.

Application filed February 24, 1922. Serial No. 538,845.

To all whom it may concern:

Be it known that I, DANIEL P. MAHONEY, a citizen of the United States of America, and resident of Cambridge, in the county of 5 Middlesex and State of Massachusetts, have invented new and useful Improvements in Coal Chutes, of which the following is a specification.

This invention concerns apparatus for handling coal or other material having generally similar physical characteristics and relates more particularly to means useful in the piling of such material for storage. In 10 the production and transportation of coal and similar material it is common to store it temporarily in piles or pockets of large capacity, the material being deposited in such piles or pockets by the use of suitable machinery. Ordinarily such machinery 15 comprises elevating means adapted to raise the material to a height at least equal to the maximum height of the pile to be formed, or to the top of the pocket, and commonly 20 has associated therewith some means for distributing the elevated material horizontally and for dumping it at the desired point. In 25 starting a new pile, or in commencing to fill an empty bin or pocket it is obvious that with the above described apparatus the coal 30 must fall through a considerable height, frequently as much as 35 or 40 feet before it strikes the ground or the bottom of the pocket. As ordinary coal is relatively brittle, the result of this mode of handling it is 35 that a large amount of coal is broken by the fall to which it is subjected, either through the direct impact of the coal with the ground or by contact with adjacent pieces of coal during the fall. As the value of coal varies 40 very considerably with its size, it is evident that substantial loss may be occasioned by this breakage; in fact in the commercial handling of certain kinds of coal, such loss, due to the breaking and pulverization of the 45 coal in storing the same may amount to as much as 4 or 5%. If the coal be subjected to several handlings during its course from the mine to the consumer, it is clear that the economic loss may thus become very considerable. In the effort to obviate such loss 50 due to breakage, various means have heretofore been devised with the object of decreas-

ing the velocity of the coal in falling as, for example, by causing it to descend over a flight of steps or shelves, but while theoretically beneficial in some instances, it has been found in actual practice that but little advantage accrues from the use of such devices, either by reason of their failure sufficiently to reduce the shock or abrasive action to 60 which the descending coal is subjected or on account of the necessity of employing additional workmen for the proper manipulation of such devices.

The object of the present invention is accordingly to provide means useful in connection with the handling of coal or similar material, whereby the coal may be fed to a pile or pocket from an elevated point without substantial breakage from falling or 65 abrasion and so constructed and arranged that the maximum permissible fall of the coal during the building of the entire pile, or the filling of the bin, shall automatically 70 be controlled so as never to exceed a pre- 75 determined amount.

In the accompanying drawings, a device is illustrated which is eminently well adapted for carrying the above object into effect, such specific device being shown however, 80 merely for the purpose of exemplifying the various arrangements of parts whereby similar and equivalent results may be obtained.

Fig. 1 is a side elevation of a coal pocket 85 of usual construction such as is commonly employed at a dock side for unloading coal from barges, a portion of the side wall of the structure being broken away to show the installation of the device of the present invention:

Fig. 2 is a side elevation of a coal elevating device of that type employed for lifting coal from a barge and for placing it in a storage pile, the device of the present invention being shown as supplied thereto;

Fig. 3 is a vertical section through an elevator structure of usual type such as is employed for storing coal and showing the device of the present invention as applied thereto;

Fig. 4 is a fragmentary side elevation to larger scale of a chute constructed in accordance with the present invention; and

Fig. 5 is a fragmentary vertical cross section on the line A—B of Fig. 4.

Referring to Fig. 1, a housing 1 is indicated, such housing being provided with a plurality of bins or pockets 2, 3, 4 respectively. Upon the top of this housing is arranged a runway for a movable motor house 5 provided with a derrick and boom 6 and with a hopper 7, the boom serving to support a skip or bucket 8 whereby coal may be lifted from a barge and delivered into the hopper 7. Within the bin 4 is arranged a hopper 9 for receiving coal from the hopper 7, and associated with such hopper 9 is a chute 10 comprising the successively inclined sections 11, 12 suspended from the upper part of the structure by means of cables 13 or in other convenient manner. The several sections of this chute are constructed substantially in accordance with the arrangement shown in Figs. 4 and 5. Each chute section is shown as comprising spaced side plates 14, 15 respectively, having elongate angle irons 16, 17 extending along their upper and lower edges whereby such plates are stiffened and properly supported. The upper angle irons are provided with suitable openings for the reception of rings 18 to which are secured the lower ends of the cables 13 by which the chute is suspended, as previously mentioned. Between the plates 14, 15 a series of floor or gate sections 19 are arranged, such floor or gate sections being provided with vertical side flanges 20, 21 respectively which lie in contact with the inner surfaces of the respective plates 14, 15. Substantially centrally of each of such floor or gate sections, a bracket 22 is provided, such brackets being secured to the under surfaces of the respective sections and providing journal means for rods or shafts 23 which extend through suitable openings in the side plates 14, 15 and which may be retained in position by means of cotter pins 24. Normally the several floor or gate sections are in substantial alignment, and for holding such sections in alignment, pins 25 are provided, such pins passing through openings in the side plates and normally projecting beneath the floor or gate sections at points adjacent the lower ends thereof. The outer ends of the pins 25 are secured as indicated at 26 to lever arms 28 having at their upper ends cross bars 29 which are pivotally secured in brackets 30 attached to the outer surface of the plates 14 and 15. As herein shown, the pins 25 with their levers and supporting brackets are disposed alternately upon opposite sides of the chute. To insure the proper tipping of the floor or gate sections when the pins 25 are withdrawn from beneath the same, such floor or gate sections are preferably provided with weights such as 31 adjacent to their forward ends, and for preventing overthrow of the

floor sections in tilting about their pivots, stop pins 32 are secured at proper points adjacent to the upper edges of the plates 14, 15, respectively. Secured to the lower end of each of the levers 28 is a plate 33, such plates preferably being so arranged as to incline outwardly from the plane of the adjacent side plate of the chute. The pins 25 may be considered to constitute latch members for holding the several floor sections in position, while the levers 28 with the plates 33 may be regarded as triggers whereby the latches are tripped for releasing the floor sections in successive order as will herein-after be more fully described.

In the device shown in Fig. 2, a pair of spaced supports 40, 41 are provided, such supports serving as foundations for the longitudinally extending parallel rails 42, 43. Mounted upon said rails is a bridge member 44 movable longitudinally thereof, such bridge member being provided with a housing 45 for the operating mechanism and with a boom 46 for supporting a skip or bucket 47 whereby coal may be lifted from a barge and deposited in a hopper, such as 48. From the hopper 48 extends a chute comprising the successive sections 49, 50, 51 suspended from the bridge member by cables 52. At 53 is indicated a coal pile of small dimensions, the parts being illustrated as they appear during the early stages of the piling operation.

In Fig. 3 the elevator structure 60 is shown as provided with a series of bins such as 61, 62, 63, and with an inclined endless conveyor 64 for raising coal or other material to the upper part of the elevator structure. A horizontal conveyor 65 is also provided whereby coal elevated to the top of the structure may be distributed into the several bins, a hopper 65 being provided for receiving the coal from the horizontal conveyor and for directing it into proper bin. Associated with this hopper is a chute comprising the successive inclined sections 67, 68, 69 respectively supported from the upper part of the elevator structure by cables 70.

In the several structures illustrated in Figs. 1, 2 and 3 respectively, the chutes are all of the type shown in detail in Figs. 4 and 5. At the beginning of the operation of filling a pocket or building a pile, the several floor sections 19 are in alignment as indicated at the upper right-hand part of Fig. 4, such sections resting upon the pins 25 which project beneath the same. As the coal is delivered into the chute, it passes downwardly over the substantially smooth and unobstructed floor of the chute until it arrives at the end of the chute where it is freely discharged. As soon as a pile of any substantial height is formed the freshly delivered coal begins to slide or run down the outer surface of the pile, and as the

pile continues to grow and rises above the level of the lowermost of the plates 33, such movement of the coal in sliding down the pile serves to swing the plate 33, with its 5 supporting lever 28 outwardly and away from the chute. This immediately withdraws the pin 25 from beneath the lowermost floor or gate section whereupon the latter swings into the position shown at 10 the lower left-hand side of Fig. 4. This serves to shorten the chute and to permit the coal to escape from over the edge of the next adjacent floor or gate section through the discharge orifice thus provided between 15 such edge and the vertically extending bottom wall of the next lower floor section, as indicated in broken lines in Fig. 4 at X. The pile continues to build up until the sliding material strikes the next plate 33, 20 whereupon the pin controlled thereby is withdrawn and the next floor or gate section in turn is rendered inoperative. This operation continues as the pile grows, it being noted, however, that the maximum 25 fall to which the coal is subjected corresponds to the vertical distance between the lower edges of successive floor sections, and that the movement of the coal during its travel through the chute is uninterrupted 30 by falls and that it drops only upon its discharge therefrom. As the floor of the chute is substantially smooth and continuous, the coal is subjected to little abrasive action during its descent, and as the maximum 35 fall may be determined within any desired limits, it is clear that the handling of the coal in this fashion serves very largely to eliminate breakage such as commonly occurs in the handling of coal, and particularly 40 during the early stages of the filling of a bin or the building of a pile. If desired, the hoppers 9, 48 and 66 as illustrated in Figs. 1, 2 and 3 respectively may be provided with doors whereby after the building 45 of the pile to any desired height, the coal may then be permitted to fall freely from the hopper on to the pile without passing through the chute. It is also clear that while herein the chute has been shown as 50 comprising a series of successive sections, such an arrangement is not necessary, but that a single section might well be employed under many circumstances or that the upper sections of the chute might well be of 55 other construction if desired, so long as the coal during the earlier stages of the operation is prevented from falling through a substantial distance.

While as herein shown, the aggregate of 60 the floor or gate sections constitutes the entire floor of the chute, it is contemplated that under certain circumstances, fixed sections might well be interposed between the movable sections, or that other arrangements 65 of movable floor section or gate might be

substituted for that specifically described herein.

While the improved chute as herein described has been disclosed as applied to certain types of coal handling apparatus, it is 70 to be understood that it is applicable to any type of apparatus and in any situation where it is desired to handle coal or other material having similar physical characteristics without subjecting the same to injurious falls or abrasion. It is also to be understood that various changes and rearrangements of parts might well be substituted for those herein specifically described whereby to secure the same results without 75 departing from the spirit of the present invention.

What I claim and desire to secure by Letters Patent of the United States is:

1. A device for use in handling coal comprising a substantially uninterrupted guideway, and means automatically operable by coal discharged therefrom for terminating the path of movement along said guideway of coal subsequently traveling therein. 85

2. In combination with material elevating and dumping means, means for receiving the material from the dumping means and for automatically discharging such material at progressively more elevated points in accordance with the growth of the mass of material previously discharged therefrom. 95

3. An inclined guideway for delivering material from a source of supply to a storage pile, and means automatically operative 100 to determine the effective length of said guideway in inverse ratio to the height of the pile.

4. A device for use in the handling of coal comprising a guideway having a plurality of normally closed gate members, and means whereby the opening of said gate members is automatically controlled by coal previously discharged from said guideway. 105

5. An inclined chute for delivering material to a pile thereof, said chute having a plurality of normally closed and aligned gate sections, and means automatically operative successively to open said gate sections beginning with the lowermost, in accordance with the progressive increase in height of the pile. 110

6. A device for use in the handling of coal comprising a guideway having a series of normally closed discharge orifices, and 115 automatically operable means for successively opening said orifices.

7. A coal handling device comprising an inclined guideway comprising a series of movable floor sections, means normally holding said sections in substantial alignment, and means whereby such sections may automatically be caused to move in orderly succession beginning with the lowermost. 125

8. A coal handling device comprising a 130

- guideway comprising a series of pivotally supported floor sections normally arranged in substantial alignment, and means operable by engagement with coal previously discharged for determining the tilting of said floor sections about their respective pivots.
9. An inclined chute having an open bottom, a series of gate members normally in alignment and constituting a floor therefor, latch devices for normally retaining said gate members in substantial alignment, and means operable by contact with material previously discharged over the lower edge of one of said gate members for releasing the latch device associated with the next adjacent member.
10. A chute for delivering material into a pile comprising a plurality of successive, downwardly inclined sections extending respectively in different directions, each of said sections having a plurality of normally closed gate members, and automatically operative means for progressively opening said gate members, beginning with the lowermost, in accordance with the growth of the pile of material.
11. An inclined chute having a substantially smooth and unobstructed bottom comprising a series of tilttable gate members, means normally retaining said gate members in substantial alignment, and a movable member depending from said chute and operable to release such gate holding means.
12. A chute for delivering material into a pile, said chute having discharge orifices, and trigger means, actuatable by contact with the growing pile of material, for determining the passage of the material through the respective orifices.
13. An inclined chute comprising a series of normally aligned floor sections, means normally retaining said sections in alignment, and actuating arms projecting downwardly from the retaining means and operable in turn by material discharged from the chute whereby to permit tilting of the floor sections in orderly succession beginning with the lowermost.
14. An inclined chute having an opening in its bottom wall, a gate for controlling said opening, latch means for normally holding said gate in closed position, and a trigger member projecting rearwardly from the chute and actuated by contact with material discharged from the chute to release said latch means.
15. An inclined chute comprising spaced side members, a series of floor sections arranged between the side members, transverse shafts mounted on the side members and constituting pivotal supports for the several floor sections, movable stop pins normally engaging the several floor sections for holding them in substantial alignment, and a trigger lever connected with each of said pins for moving its pin out of engagement with the respective floor section to permit the latter to tilt about its pivotal support.
16. A chute comprising a pair of parallel spaced side plates, a series of shafts extending from one to the other of the plates adjacent to the lower edges of the latter, a floor section pivotally mounted on each shaft, one end of each floor section being heavier than the other, pins arranged to slide in openings in the side plates and normally underlying the heavy ends of the floor sections to hold the latter in substantial alignment, levers pivoted to the side plates, means connecting a lever to each pin, and a plate secured to the free extremity of each lever for engagement by material discharged from the chute.
17. An inclined chute comprising a pair of spaced, parallel side plates, a series of pivotally supported floor sections arranged between said plates and normally aligning with one another, flanges projecting upwardly from opposite edges of each floor section and contacting with the inner walls of the side plates respectively, a latch member normally engaging each floor section for holding it in operative position, and a trigger lever connected with each latch for actuation by moving material discharged from the chute.
18. An inclined chute comprising a pair of parallel, vertical side plates, a series of shafts extending from one plate to the other, floor sections each having a bracket secured to its under side, said brackets being pivotally supported upon the respective shafts, a weight secured to the lower end of each floor section for causing it to tilt about its pivotal axis, a movable latch pin associated with the weighted end of each floor section for normally holding the several sections in alignment with each other, pivotally supported trigger levers connected with the respective latch pins, and a plate secured to the free extremity of each trigger lever in position to be moved by contact with moving material discharged from the chute.
19. An inclined chute having spaced side plates and a floor comprising a series of normally aligned, movable sections, each section being provided with a slidable latch pin arranged in an opening in a side plate and normally engaging its corresponding floor section, a lever pivoted at its upper end to one of the side plates, means connecting said latch pin to the lever at a point midway the length of the latter, and a plate secured to the free extremity of the lever and extending below the bottom of the chute in position to be moved by material newly discharged from the chute and sliding down the sides of the accumulated pile of such material.

20. An inclined chute having a floor comprising a series of relatively movable sections, latch devices normally engaging the respective sections for holding them in normal position, a trigger lever connected to each of such latch devices for moving the latter out of operative position, and a plate secured to the free extremity of each lever, said plates being inclined outwardly with respect to the vertical plane of the axis of the chute.
- 5 Signed by me at Boston, Massachusetts, this eighteenth day of February, 1922.

DANIEL P. MAHONEY.
